UNITED STATES PATENT OFFICE

WILLIAM H. PARRY, OF MALDEN, MASSACHUSETTS, ASSIGNOR TO GILLETTE SAFETY RAZOR COMPANY, OF BOSTON, MASSACHUSETTS, A CORPORATION OF DELAWARE

SAFETY RAZOR

Application filed May 15, 1929. Serial No. 363,247.

This invention relates to safety razors of the type in which a cap and a guard member are adapted to be clamped together upon a thin flexible blade to hold it in position for 5 shaving, or to be separated to release the blade for removal and replacement.

It is desirable in a razor of this type that the clamping engagement of the cap and guard should be effected quickly in preparing 10 the razor for use and that they should be disengaged with equal facility after use when it is desired to remove the blade and clean the razor. It is also important that the engagement of the cap and guard should 15 be made firmly under adequate pressure and reliably maintained while the razor is being used. The latter condition is essential because any loosening of the razor parts permitting an increase of the edge exposure of 20 the blade while the razor is being used renders it extremely dangerous to the user.

I have discovered a construction which successfully meets the requirements above outlined and possesses also the mechanical advantages of compactness in design and 25 convenience of manufacture.

In one aspect accordingly my invention consists in a safety razor comprising a cap having a stud with an enlarged head provided 30 with a longitudinal passage in one side thereof, a guard and a handle adapted to clamp the two together by interlocking with the stud of the cap and for this purpose having a bore of sufficient diameter to receive 35 the head of the stud and an internal projection adapted to pass through the passage therein and interlocking with it. By providing an inclined contact face between the internal projection of the handle and the cap 40 stud, the cap and guard may be drawn together under powerful pressure by a slight rotation of the handle, and when the desired clamping engagement has been once effected there is no tendency, while the razor is being 45 used, to disturb this relation.

These and other features of the invention will be best understood and appreciated from the following description of a preferred embodiment thereof, selected for purposes of 50

illustration and shown in the accompanying drawings in which:

Fig. 1 is a view in perspective of the cap member of the razor.

Fig. 2 is a view in perspective of the handle 55 with portions broken away.

Fig. 3 is a sectional view of the cap member.

Fig. 4 is a view of the razor partly in elevation and partly in section, showing the 60 parts thereof assembled but not clamped.

Fig. 5 is a sectional view of the line 5—5 of Fig. 4.

Fig. 6 is a view similar to Fig. 4 but showing parts of the razor in clamped condition, 65 and

Fig. 7 is a sectional view on the line 7—7 of Fig. 6.

In the preferred embodiment of the razor, the cap 10 comprises a transversely curved 70 bar having an inner concave blade-shaping surface and an exterior convex face. From the concave face of the cap extends a pair of cylindrical locating studs 12 spaced equally from the ends of the cap. A center stud 14 also projects from this surface, being provided with a collar 15 adjacent to the face of the cap and with an enlarged cylindrical head 16 at its outer end. The inner or overhanging face of the head 16 is inclined or spiral 75 in shape, for a purpose which will presently appear, and one side of the head 16 is provided with a longitudinally extending groove or channel 17.

The guard member 22 of the razor is perforated to receive the locating studs 12 and the center stud 14. It is provided at either edge with a series of guard teeth and with a blade-engaging face having a pair of parallel fulcrum shoulders 23 similar to those of the guard member disclosed in U. S. Patent No. 1,328,024 granted January 13, 1920. In the assembled razor the flexible blade is bent over the shoulders 23 by the concave blade-shaping face of the cap. 85

The handle of the razor may be of any desired shape so long as it cooperates with the center stud 14 of the cap member. As herein shown the handle 24 is tubular in form and somewhat concave at its inner end so 90

as to present a fair bearing against the outer face of the guard 22. In its diameter the bore of the handle is substantially equal to the diameter of the cylindrical head 16 of the cap stud. Adjacent to its end the bore is provided with an internal rib 26 corresponding in cross section substantially to the cross sectional area of the channel 17 in the head 16 of the cap stud and of such length as to fit with a slight clearance beneath the overhanging surface of the head 16 when the parts of the razor are assembled in their respective initial positions as shown in Fig. 4. The rib 26 at its outer end extends substantially flush with the end or guard engaging face of the handle.

The blade 20 comprises a thin flexible double-edged blade perforated to receive the locating studs 12 and the collar 15 of the center 20 cap stud 14. The blade is accurately positioned transversely between the cap and guard by these studs and is curved into substantial conformity to the concave face of the cap 10 when the parts are drawn into 25 clamping relation.

In assembling the illustrated razor for use, the parts are brought together in the condition shown in Fig. 4, that is to say, the blade 20 and the guard 22 are threaded upon 30 the studs of the cap 10 and the center stud 14 is inserted in the bore of the handle, the rib 26 passing through the channel 17 of the head 16. The shape and slope of the overhanging or undercut surface of the head 35 16 is such that when the handle 24 is turned in a clockwise direction as seen in Figs. 5 and 7 the inner end of the rib 26 will coat with the overhanging surface of the stud to draw the stud inwardly and move it into clamping 40 relation with the guard 22, as shown in Fig.

6. In effecting this motion the rib 26 which originally coincides in angular position with the channel or groove 17 is moved angularly through substantially 120 degrees to the 45 dotted line position indicated in Fig. 7. It may be noted that the collar 15 adjacent to the cap 10 extends beyond a line joining the effective edges of the cap, thus ensuring registration of the collar with the hole in the 50 guard plate before the application of tension to the blade 20 by rotation of handle 24.

In order to release the cap and guard from clamping position it is necessary only to turn the handle back to its initial position 55 bringing the rib 26 again into registration with the groove 17, whereupon the cap is free to be separated from the guard, the head 16 being free to be longitudinally removed out of the bore of the handle.

60 Having thus disclosed my invention and described a preferred embodiment thereof, what I claim as new and desire to secure by Letters Patent is:—

1. A safety razor comprising a guard plate 65 having a blade shaping surface and a

stud receiving hole, a cooperating cap having a concaved surface with substantially parallel longitudinal edges, a tubular handle having a guard engaging end and a rib on its inner surface extending substantially flush with said guard engaging face, and a stud projecting from the concaved surface of said cap having at its outer end an enlarged slotted collar fitting the inside surface of said tubular handle and provided with an angular inner face, a second collar adjacent the fixed end of said stud fitting within the hole in said guard plate, said collar extending beyond a line joining the longitudinal edges of said cap, and said stud having a neck of reduced diameter connecting said collars.

2. A safety razor comprising a cap and a cooperating guard adapted to hold a blade between them, a short stud projecting outwardly from the blade engaging face of the cap and having a cylindrical enlargement at its free end, a handle having an end face for engaging the guard and a cylindrical bore in one end for receiving and fitting said enlargement, the inner end wall of the enlargement being inclined to provide a cam like shoulder, and one side portion of the enlargement being slotted from its outer end through the said inclined wall, and an inwardly projecting lug of substantial length located within the bore of the handle and extending to the guard engaging face thereof for passing through the slot and engaging against the said end wall, a portion of the 100 stud inwardly from said end wall being of reduced diameter.

Signed at Boston, Massachusetts, this 14th day of May, 1929.

WILLIAM H. PARRY.
